UNITED STATES PATENT OFFICE.

CLAUS OTTE, OF ANAHEIM, CALIFORNIA.

ROPE CINCH.

Application filed May 21, 1928. Serial No. 279,258.

This invention relates to rope tightening devices, and has for an object the provision of a rope cinch by means of which a rope may be drawn taut.

5 Another object is the provision of a rope cinch as described, adapted to remain in that position in which the rope is held taut until manually and intentionally released.

Another object is the provision of a rope 10 cinch of the general character described, having a plurality of fingers upon the link, to which the rope is to be attached by means of which the fastening process is facilitated.

15 My invention possesses other objects and features of advantage, some of which, with the foregoing, will be set forth in the following description of the preferred form of the invention which is illustrated in the 20 drawings accompanying and forming part of the specification. It is to be understood that I do not limit myself to the showing made by the said drawings and description, as I may adopt variations of the preferred 25 form within the scope of my invention as set forth in the claims.

Referring to the drawings:

Figure 1 is a side elevation of a motor truck having the improved rope cinch of 30 my invention installed thereupon so as to draw a rope taut over the load carried by the truck, to retain the load in position.

Fig. 2 is an enlarged view of my improved rope cinch in side elevation, and showing 35 the operative parts thereof in the positions assumed thereby before being moved to rope-tightening position.

Fig. 3 is a side elevation of the cinch of Fig. 2, showing a rope attached thereto and 40 showing the operative parts moved to the positions assumed thereby after they have been moved to rope-tightening position.

Fig. 4 is a rear elevation of the device of Fig. 3, the direction of view being indicated 45 by the arrow 4 of that figure.

Fig. 5 is a top plan view of the link to which the rope is attached, the direction of view being indicated by the arrow 5 of Fig. 2.

50 Fig. 6 is a fragmentary view showing a modified form of attaching bracket.

In terms of broad inclusion, the improved rope cinch of the present invention comprises a bracket adapted to be rigidly secured to a 55 supporting structure, with a portion thereof projecting outwards from that structure to

provide a pivotal connection for a tightening lever. A link is pivoted to the lever at a point spaced from the pivoted end of the lever so that when the lever is swung upon its pivotal mounting, the link is moved longitudinally.

The parts are so arranged and proportioned that before the lever completes its swinging movement, it passes the dead center position in respect to the direction of pull of the link, with the result that this pull tends to retain the lever with the link at the extreme of its movement. Means are provided at the other end of the link for 70 attaching a rope thereto so that after the rope has been secured to the link, the lever may be swung on its pivotal mounting to tighten the rope; and then by completing the pivotal movement of the lever, the 75 parts locked in rope-tightening position against inadvertent displacement thereof until the lever be swung in a reverse direction manually and intentionally. Accordingly, my invention finds a particular 80 field of utility in conjunction with such vehicles as motor trucks, where it may be employed to draw a rope taut over the load on the vehicle to prevent displacement of the 85 load during transportation.

Specifically describing the preferred embodiment of my invention, I have provided a bracket 6 having an offset portion 7 through which any suitable attaching means such as bolts, may be extended into the frame 8 or other portion of a vehicle 9 to rigidly 90 attach the bracket 6 thereto. A portion 11 of the bracket extends rearwards thereof and is provided with an aperture through which a bolt 12 or its equivalent may extend to provide a pivotal mounting for the bifurcated end 13 of a lever 14 with the portion 11 disposed within the bifurcation 13.

A link 16 is provided by means of which 100 a rope 17 may be operatively connected to the lever 14 to tighten the rope 17 by downward swinging of the lever 14. The lower end 18 of the link 16 is also bifurcated with a portion 19 of the bifurcation bowed outwards to form an eye adapted to pass over the bifurcation 13 and the portion 11 of the bracket 6 as well as the bolt 12 extending therethrough.

As a result, the link 16 may be swung 110 downwards upon its pivotal mounting 12, carrying with it the link 16 until the eye

19 passes over the bolt 12 and is engaged by a pair of rigid wings 21 extending laterally from the bracket 6 as shown in Fig. 3.

I have found it convenient to construct 5 the link 16 from two separate strips of metal, one of which is bent at its center portion to provide the circular eye 19 with the ends of the strip extending from one side of the 10 circle and then by welding the other strip 15 to the circle diametrically opposite the ends the first strip. This second strip forms the straight portion 22 of the link upon which means are provided for attaching the rope 17 thereto. In its preferred form, the 20 entire link is slightly bowed edgewise, with the center portion of the bow extending away from the bracket 6, as clearly shown in Figs. 2 and 3.

The means for attaching a rope to the 25 cinch, comprises a plurality of fingers rigid with the straight portion 22 of the link 16. The uppermost finger 23 is hook shaped and is bent over to extend beyond one side 24 of the link from the top thereof, with the 30 open side 26 of the hooked finger 23 directed across the link toward the other side 27 thereof. The next adjacent finger 28 is positioned below the finger 23 and extends from the after edge 29 of the straight portion 35 22 of the link 16. The finger 28 is reversely bent to extend beyond the side 27 to present a hook with the open side 31 thereof extending forwards across the link toward the other edge 32 thereof. The 40 lowermost finger 33 is also hook shaped, with the open side 34 of the hook extending angularly downwards, and with the hook 33 extending beyond the side 24 of the straight portion 22 of the link 16.

The bracket 6 is particularly designed 45 for mounting my improved rope cinch upon the frame 8 of a vehicle 9. It is intended that the offset portion be secured to the under side of the frame by suitable bolts or their equivalent, so that the portion 11 extends rearwards of the vehicle. However, if it be 50 more convenient to attach the cinch to a vertical surface instead of a horizontal surface, a bracket of the type shown in Fig. 6 may be employed wherein the fastening means are intended to be passed through suitable 55 apertures in the body portion 6' and which has a fulcrum portion 11' similar to the portion 11 of the embodiment previously described.

One manner of attaching a rope to the link 22 by means of the fingers 23, 28 and 33 is as follows:

The rope 17 is carried downwards and 60 inserted as at 36 into the hook 23 and thence downwards about the after side of the hook 33, and as at 37 wound thereabout to extend upwards around the forward side of the hook 33. A half hitch 38 is then thrown over the hook 28 with that portion 39 of the rope

extending from the hook 33, passing over the hook 28 and thence around the same, with the end 41 of the rope extending under the portion 39, and between the portion 39 and the portion 42 extending between the hook 70 23 and the hook 33. Thus it may be seen that when the standing portion of the rope 75 17 has tension imposed thereupon, the portion 42 bears outwards against the end 41 and the portion 39 bears inwards against the portion 41, with the result that the rope 17 is securely attached to the link 16 without any additional tying being necessary.

The rope 17 should be attached to the link 16 in the manner described, or in any 80 other convenient manner with the lever 14 in the position indicated in Fig. 2. The lever 14 may then be swung downwards upon its pivot 12, causing the link 16 to be pulled longitudinally downwards to impose tension 85 upon the rope 17. It is to be understood of course, that when the device is employed to retain a load 46 upon the vehicle 9, that the other end of the rope 17 has previously been attached in suitable position to the 90 vehicle. The swinging movement of the lever 14 is continued until the dead center position has been passed; or in other words, until the eye 19 has passed over the pivotal connection 12 between the lever 14 and the 95 portion 11 of the bracket 6. After this has been done, the tension upon the rope 17 urges the lever 14 upwards in the same direction about its pivot 12; but this continued movement of the lever 14 is stopped 100 by the wings 21. As a result, the tension of the rope 17 serves to retain the parts in tightening position from which they can not be inadvertently displaced to release the tension on the rope. However, such release 105 may easily be effected by swinging the lever 14 in a reverse direction, after which the rope 17 may be easily disengaged from the link 16.

I claim:

1. A rope cinch comprising a bracket adapted to be rigidly attached to a supporting structure with a portion of the bracket extending outwards from the structure, a lever pivoted at one end to the extended portion of said bracket, a link bifurcated at one end and pivoted to said lever at a point spaced from the pivoted end of the lever, and with the lever disposed within the bifurcation thereof, a portion of the bifurcation being bowed outwards to form an eye adapted to pass over the pivoted connection between the bracket and lever, and means at the other end of said link for attaching a rope thereto.

2. A rope cinch comprising a bracket adapted to be rigidly attached to a supporting structure with a portion of the bracket extending outwards from the structure, a lever pivoted at one end to the extended 120 portion of said bracket, a link bifurcated at one end and pivoted to said lever at a point spaced from the pivoted end of the lever, and means at the other end of said link for attaching a rope thereto.

- portion of said bracket, a link bifurcated at one end and pivoted to said lever at a point spaced from the pivoted end of the lever and with the lever disposed within the bifurcation thereof, a portion of the bifurcation being bowed outwards to form an eye adapted to pass over the pivoted connection between the bracket and lever, wings extending laterally from said bracket to engage said link and limit the movement thereof in passing over said pivotal connection, and means at the other end of said link for attaching a rope thereto. 55
5. In a rope cinch, a link, means associated with said link for pulling it longitudinally and for locking it at the end of such longitudinal movement, and a plurality of fingers projecting from said link about which a rope may be twisted to secure the rope to the link. 60
10. In a rope cinch, a link, means associated with said link for pulling it longitudinally and for locking it at the end of such longitudinal movement, and a plurality of fingers projecting from said link about which a rope may be twisted to secure the rope to the link. 65
15. In a rope cinch, a link, means associated with said link for pulling it longitudinally and for locking it at the end of such longitudinal movement, and a plurality of fingers projecting from said link about which a rope may be twisted to secure the rope to the link. 70
20. In a rope cinch, a link, means associated with said link for pulling it longitudinally and for locking it at the end of such longitudinal movement, and a plurality of hooked fingers projecting from said link about which a rope may be twisted to secure the rope to the link. 75
25. In a rope cinch, a link, means associated with said link for pulling it longitudinally and for locking it at the end of such longitudinal movement, and a plurality of fingers projecting from said link about which a rope may be twisted to secure the rope to the link, the uppermost of said fingers being hook shaped and extending to one side of the link from the top thereof with the open portion of the hook directed across the link toward the other side thereof, another of said fingers extending from an edge 80
30. of the link and being reversely bent toward the second mentioned side of the link, and the lowermost of said fingers extending from the link to that side thereof toward which the first mentioned hook extends. 85
35. In a rope cinch, a link, means associated with said link for pulling it longitudinally and for locking it at the end of such longitudinal movement, and a plurality of fingers projecting from said link about which a rope may be twisted to secure the rope to the link, the uppermost of said fingers being hook shaped and extending to one side of the link from the top thereof with the open portion of the hook directed across the link toward the other side thereof, another of said fingers extending from an edge 90
40. of the link and being reversely bent toward the second mentioned side of the link, and the lowermost of said fingers extending from the link to that side thereof toward which the first mentioned hook extends. 95
45. In a rope cinch, a link, means associated with said link for pulling it longitudinally and for locking it at the end of such longitudinal movement, and a plurality of fingers projecting from said link about which a rope may be twisted to secure the rope to the link, the uppermost of said fingers being hook shaped and extending to one side of the link from the top thereof with the open portion of the hook directed 100
50. toward which the first mentioned hook extends. 105
- across the link toward the other side thereof, another of said fingers extending from an edge of the link and being reversely bent toward the second mentioned side of the link, and the lowermost of said fingers being bent downwards and extending from the link to that side thereof toward which the first mentioned hook extends.
7. A rope cinch comprising a bracket adapted to be rigidly attached to a supporting structure with a portion of the bracket extending outwards from the structure, a lever pivoted at one end to the extended portion of said bracket, a link pivoted to said lever at a point spaced from the pivoted end of the lever, the pivoted end of said link being bowed outwards and adapted to pass the pivoted connection between the bracket and lever, and means at the other side of said link for attaching a rope thereto. 75
8. An attaching device comprising a link and a plurality of fingers projecting from said link about which a rope may be twisted to secure the rope to the link, the uppermost of said fingers being hook-shaped and extending to one side of the link from the top thereof with the open portion of the hook directed across the link toward the other side thereof, another of said fingers extending from an edge of the link and being reversely bent toward the second mentioned side of the link, and the lowermost of said fingers extending from the link to that side thereof toward which the first mentioned hook extends. 80
9. An attaching device comprising a link and a plurality of fingers projecting from said link about which a rope may be twisted to secure the rope to the link, the uppermost of said fingers being hook-shaped and extending to one side of the link from the top thereof with the open portion of the hook directed across the link toward the other side thereof, another of said fingers extending from an edge of the link and being reversely bent toward the second mentioned side of the link, and the lowermost of said fingers being bent downwards and extending from the link to that side thereof toward which the first mentioned hook extends. 85
10. In testimony whereof I have signed my name to this specification.

CLAUS OTTE.
